UNITED STATES PATENT OFFICE.

WILLIAM S. SCHROEDER AND ANDREW P. LINDHOLM, OF CHICAGO, ILLINOIS, ASSIGNORS TO CHARLES H. FERRY, OF CHICAGO, ILLINOIS.

CAR-COUPLING.

SPECIFICATION forming part of Letters Patent No. 783,985, dated February 28, 1905.

Application filed January 4, 1904. Renewed December 28, 1904. Serial No. 238,688.

To all whom it may concern:

Be it known that we, WILLIAM S. SCHROEDER and ANDREW P. LINDHOLM, citizens of the United States, residing in Chicago, in the county of Cook and State of Illinois, have invented a new and useful Improvement in Car-Couplers, of which the following is a specification.

Our invention relates to car-couplers of the M. C. B. or Master Car-Builders' type, having a forked draw-head, pivoted knuckle, and a gravity-lock consisting of a longitudinal pivotal locking-bar lying in the chamber of the draw-bar and having a pivotal connection therewith at its inner end and engaged near its outer end by a vertically-moving coupling-pin or lifting-pin which is connected in the usual manner by a chain with the lifting-lever. Couplers of this particular kind, having a longitudinal pivotal locking-bar lying in the chamber of the draw-head, have not heretofore had means for setting the lock to uncouple or for throwing the knuckle open.

The object of our invention is to provide a longitudinal pivotal locking-bar coupler of a simple, efficient, practical, and durable construction, in which the lock may be set in position for uncoupling and in which the knuckle may be automatically thrown open.

Our invention consists in the means we employ to practically accomplish this object or result—that is to say, it consists, in connection with the forked draw-head and pivoted knuckle, of a longitudinal pivotal locking-bar lying in the chamber of the draw-bar and having a slight longitudinal or forward movement to adapt it to engage a hook or shoulder on the draw-head when its forward end is raised to the unlocking position, thus providing the coupler with a simple and efficient lock-set.

It further consists, in connection with the forked draw-head, pivoted knuckle, and longitudinal pivotal locking-bar lying in the chamber of the draw-bar and a coupling or lifting-pin by which the forward end of the locking-bar is raised to unlock the coupler, of a knuckle-throwing lever having an arm adapted to engage the locking-bar as it is raised by the

lifting-pin and furnished with a curved arm which engages the tail of the knuckle to throw the knuckle open, this knuckle-throwing lever having also a pivot-arm fitting in a hole or recess in the draw-head.

Our invention further consists in the novel construction of parts and devices and in the novel combinations of parts and devices herein shown or described.

In the accompanying drawings, forming a part of this specification, Figure 1 is a central vertical section of a longitudinal pivotal locking-bar coupler embodying our invention. Fig. 2 is a similar view showing the locking-bar in its raised or lifted position. Fig. 3 is a horizontal section on line 3 3 of Fig. 1. Fig. 4 is a detail horizontal section on line 4 4 of Fig. 1. Fig. 5 is a cross-section on line 5 5 of Fig. 1. Fig. 6 is a detail top or plan view of a portion of the draw-head, showing the shape of the opening therein to receive the locking or lifting-pin. Fig. 7 is a detail perspective view of the locking or lifting pin. Fig. 8 is a detail side elevation of the longitudinal pivotal locking-bar. Fig. 9 is a detail elevation showing the other side of same. Fig. 10 is a front end view of the locking-bar, and Fig. 11 is a detail perspective view of the knuckle-throwing lever.

In the drawings, A represents the draw-bar; A', the forked draw-head, having the customary pivot-arm A² and guard-arm A³.

B is the knuckle, pivoted to the draw-head by the pivot-pin C and having a tail B, which is engaged by the longitudinal pivotal locking-bar D, which fits and lies in the chamber a of the draw-bar.

F is the coupling or lifting pin by which the outer or free end of the longitudinally-extending pivotal locking-bar D is operated or lifted to unlock the coupler or permit the knuckle to swing open, and F' is a pivotal link or chain connecting the coupler or lifting pin with the arm F² of the lifting-lever F³, and G is the knuckle-throwing lever.

The draw-bar A is provided inside the chamber a on its lower web or floor with integral saddles or ribs a', having elongated pivot

notches or recesses a^2 therein to receive the pivot-lugs d at the rear end of the locking-bar D, the pivot notches or slots a^2 being long enough to permit the necessary longitudinal movement of the locking-bar to enable the lock-set hook or ledge d' at the front end of the locking-bar to engage a corresponding lock-set hook or ledge a^3 on the front wall a^4 of the draw-head when the front end of the locking-bar is raised. The elongated notch or recess a^2 has an inclined bottom a^5 , which aids in returning the locking-bar longitudinally to position and also serves to slightly raise the rear end of the locking-bar when in its forward position, thus diminishing the inclination of the pivotal locking-bar when its front end is raised to the lock-set position.

The locking-bar D is provided at its front end with a chamber d^2 , having an opening d^3 large enough to receive the head or shoulder f on the coupling-pin F and provided with a slot d^4 to receive the web f' , which connects the head or shoulder f with the coupling-pin F.

The draw-bar A is provided with a guide-rib a^6 to engage the front or enlarged end of the locking-bar and keep the same in position laterally while permitting the locking-bar to be raised as required at its front end. The pivotally and longitudinally movable locking-bar D is provided with inclined notches d^5 , to receive and engage the head f of the locking or lifting pin F. The locking-pin F fits in an opening a^7 in the top wall a^8 of the draw-head and is provided with an irregularity or rib f^2 , which prevents its being turned wrong when it is put in place. The lock-set hooks or ledges d on the locking-bar D and a^9 on the draw-head are provided with inclined meeting faces d^6 and a^9 , respectively, to insure the lock-set hooks or ledges passing each other when the locking-bar is raised and properly engaging with each other. To cause the locking-bar D to be thrown or moved longitudinally forward as it is raised by the coupling-pin or locking-pin F, the draw-head is provided with a projection or fulcrum a^{10} , which causes its upper end to tilt backward and its lower end to move forward when acted upon by the lifting-lever arm F.

The knuckle-throwing lever G has a pivot arm or projection g , which fits in a suitable recess or notch a^{11} in the draw-head, and an actuating web or arm g' , which fits over the front end of the locking-bar D and is engaged thereby when the front end of the locking-bar is sufficiently lifted, and it also has a curved or horn-shaped arm g^2 , which engages and follows the tail of the knuckle to throw the same open. The knuckle-throwing lever has both a rocking movement about its pivot-arm as an axis and also a swinging movement about the end of its pivot-arm as a fulcrum, thus giving the curved or horn-shaped operating-arm which engages the knuckle a combined or compound movement that causes it to prop-

erly follow the path of the tail of the knuckle in pushing or throwing the knuckle open. When the flat arm g' of the knuckle-throwing lever is engaged by the front end of the locking-bar D as it moves upward, it tends to tilt or swing the knuckle-throwing lever about the end of its pivot-arm g as a fulcrum for the lever and at the same time rock or rotate the knuckle-throwing lever about its arm g as an axis, thus giving its curved or horn-shaped operating-arm g^2 , which engages the tail of the knuckle, a combined or resultant movement due to these two motions of the lever, which causes the knuckle-throwing lever, though mounted above the knuckle, to keep its curved arm g^2 in proper engagement with the tail of the knuckle as it is swung open thereby. To cause the flat or web arm of the knuckle-throwing lever G to be properly engaged by the locking-bar D, the locking-bar is provided at its front end with a projection d^7 , that engages the web or flat arm of the knuckle-throwing lever after the front end of the locking-bar is raised sufficiently to permit the side of the knuckle to move along the same. The chamber a^{12} in the draw-head for the arm g^2 of the knuckle-throwing lever G has a rib a^{13} extending across it to serve as a guide, rest, and support for the knuckle-throwing-lever.

We claim—

1. In a car-coupler, the combination with a pivoted knuckle, a forked draw-head and a draw-bar having a chamber to receive a longitudinal pivotal locking-bar, of a pivotal and longitudinally-movable locking-bar lying lengthwise in the chamber of the draw-bar, and provided at its front end with a lock-set hook or ledge and a coupling or lifting pin connected with the front or free end of the locking-bar, said draw-head having a lock-set hook or ledge to engage the lock-set hook or ledge on the locking-bar when the same is raised and moved longitudinally forward by the lifting-pin, substantially as specified.

2. In a car-coupler, the combination with a pivoted knuckle, a forked draw-head and a draw-bar having a chamber to receive a longitudinal pivotal locking-bar, of a pivotal and longitudinally-movable locking-bar lying lengthwise in the chamber of the draw-bar, and provided at its front end with a lock-set hook or ledge and a coupling or lifting pin connected with the front or free end of the locking-bar, said draw-head having a lock-set hook or ledge to engage the lock-set hook or ledge on the locking-bar when the same is raised and moved longitudinally forward by the lifting-pin, and a knuckle-throwing lever having a pivot-arm engaging a recess in the draw-head, an arm adapted to engage the front end of the locking-bar when the same is raised and an operating-arm engaging the tail of the knuckle to throw the same open, substantially as specified.

3. In a car-coupler, the combination with a pivoted knuckle, a forked draw-head and a draw-bar having a chamber to receive a longitudinal pivotal locking-bar, of a pivotal and longitudinally - movable locking - bar lying lengthwise in the chamber of the draw-bar, and provided at its front end with a lock-set hook or ledge and a coupling or lifting pin connected with the front or free end of the locking-bar, said draw-head having a lock-set hook or ledge to engage the lock-set hook or ledge on the locking-bar when the same is raised and moved longitudinally forward by the lifting-pin, and a knuckle-throwing lever having a pivot-arm engaging a recess in the draw-head, an arm adapted to engage the front end of the locking-bar when the same is raised and a curved operating-arm engaging the side of the knuckle to throw the same open, said knuckle-throwing lever having a rocking movement about its pivot-arm as an axis and a swinging movement about the end of its pivot-arm as a fulcrum, substantially as specified. 50
- 5 4. In a car-coupler, the combination with a pivoted knuckle, a forked draw-head and a draw-bar, of a pivotal locking-bar lying lengthwise in the chamber of the draw-bar, a coupling or lifting pin connecting with the free or front end of the locking-bar, and a knuckle-throwing lever mounted in the chamber of the draw-bar, and having an arm adapted to be engaged by the front end of the locking-bar when the same is raised, and an operating-arm 55 engaging the side of the knuckle to open the same, substantially as specified. 60
- 10 5. In a car-coupler, the combination with a pivoted knuckle, a forked draw-head and a draw-bar, of a pivotal locking-bar lying lengthwise in the chamber of the draw-bar, a coupling or lifting pin connecting with the free or front end of the locking-bar, and a knuckle-throwing lever mounted in the chamber of the draw-bar, and having an arm adapted to be engaged by the front end of the locking-bar when the same is raised, and an operating-arm 65 engaging the side of the knuckle to open the same, substantially as specified. 70
- 15 6. In a car-coupler, the combination with a pivoted knuckle, a forked draw-head and a draw-bar, of a pivotal locking-bar lying lengthwise in the chamber of the draw-bar, a coupling or lifting pin connecting with the free or front end of the locking-bar, and a knuckle-throwing lever mounted in the chamber of the draw-bar, and having an arm adapted to be engaged by the front end of the locking-bar when the same is raised, and an operating-arm 75 engaging the side of the knuckle to open the same, said knuckle-throwing lever having a pivot-arm fitting in a recess in the draw-head, said knuckle-throwing lever having a rocking movement about its pivot-arm as an axis, and also a swinging movement about the end of its pivot-arm as a fulcrum, substantially as specified. 80
- 20 7. In a car-coupler, the combination with a knuckle, a forked draw-head and a draw-bar having a chamber to receive a longitudinal pivotal locking-bar, of a longitudinal pivotal locking-bar lying lengthwise in the chamber of the draw-bar and having a pivotal connection therewith at its rear end adapted to permit a limited longitudinal movement of the locking-bar, and a lifting-pin connected to the front end of the locking-bar, and having a fulcrum - like bearing on the draw-head to cause the locking-bar to move slightly longitudinally forward as it is raised, said locking-bar and draw-head being furnished with lock-set hooks or ledges, substantially as specified. 85
- 25 8. In a car-coupler, the combination with a forked draw-head and a draw-bar, of a pivoted knuckle, and a pivotal locking - bar lying lengthwise in the chamber of the draw-bar, and a lifting-pin, said locking-bar and draw-head being furnished with interengaging lock-set hooks or ledges, substantially as specified. 90
